UNITED STATES PATENT OFFICE.

MICHAEL BECK, OF MINNEAPOLIS, ASSIGNOR OF ONE-HALF TO JOHN WOLSFELD, OF LONG LAKE, MINNESOTA.

COMBINED OIL-GAS GENERATOR AND BURNER.

SPECIFICATION forming part of Letters Patent No. 503,399, dated August 15, 1893.

Application filed December 19, 1892. Serial No. 455,603. (No model.)

To all whom it may concern:

Be it known that I, MICHAEL BECK, a citizen of the United States, residing at Minneapolis, in the county of Hennepin and State of Minnesota, have invented certain new and useful Improvements in a Combined Oil-Gas Generator and Burner; and I do hereby declare the following to be a full, clear, and exact description of the invention, such as will enable others skilled in the art to which it appertains to make and use the same.

My invention relates to combined oil-gas generators and burners; and has for its object to provide a more efficient device of this class.

As is well-known, in this class the oil is converted into a gas, by heat from the burner.

My invention is in the nature of an improvement in the construction and arrangement of the parts whereby I gain economy both as to the cost of the article and as to the amount of oil required. The invention is especially designed for use, in burning crude petroleum. It is also capable of use, however, with slight modification, on some other kinds of oil.

My invention consists of certain novel devices and arrangement of devices, which will be hereinafter fully described and will be defined in the claims.

My invention is illustrated in the accompanying drawings, wherein like letters refer to like parts throughout.

Figure 1 is a horizontal section through the fire-pot of a furnace or other heater on the line X X' of Fig. 2. Fig. 2 is a transverse vertical section, on the line Y Y', of Fig. 1; and Fig. 3 is a horizontal section, on the line Z Z' of Fig. 2.

A represents the side walls, and B the conical like bottom of a fire-pot, such as is used or may be used for an ordinary furnace, or other heat appliance.

C is a cup or pan-like casting, located under the center of the bottom B and secured thereto. This central casting C, is provided with air inlet passages C' and drip C².

D is a conical casting, provided at its apex with four hollow projections, d, which pass through a central opening provided for the purpose, in the fire-pot bottom B, and are secured to the horizontal part of the central

casting C. These projections d therefore serve as legs, for supporting the conical casting D, apex downward, and at the proper distance from the conical fire-pot bottom B. Through two of the hollow legs d, pass as shown, screw-threaded bolts d', the heads of which engage with the central casting C, and secure the cone D thereto in its proper working position. The oil and gas supply-pipe E E' E² passes through the other hollow legs d of the cone D, to burner F, located in the central space, between the four legs d of the cone D, and secured to or in the central casting C. The in-leading section E, of the supply pipe, extends to a supply of crude petroleum or other oil being used, under pressure, (not shown.) The pressure may be obtained in any suitable way, either by the head afforded by an elevated reservoir, or by the application of power to the oil. The section E' of the oil and gas supply pipe or conduit, is arranged in the form of a conical helix, wound about the under surface of the cone D, and partially embedded in corresponding grooves or seats formed therein. The section E² of the supply pipe taps the coiled section E' at the rim of the cone D, and extends down and through the right hand hollow leg d to the burner F. The four legs d, supporting the cone D, are spaced apart from each other; and the central casting, C is larger than the central opening in the conical fire-pot bottom B, so as to leave an air-chamber around the burner F and the legs d, into which the free air may enter through the passages C'. The cone D is provided at its apex with a central small opening, which is normally closed, by a stopper D', as shown in Figs. 1 and 2.

The operation is as follows:—To start the action, the stopper D' is removed and little waste or scraps of paper is inserted through the opening, about the burner F. The oil is then permitted to flow through, until the waste is slightly saturated, and the waste is then lighted, and the stopper D' restored to its position. The heat from the waste and burning oil will then take effect on the coiled section E' and generate a gas from the oil contained therein, which will be burned at the burner F. Thereafter, the operation will con-

tinue. The heat from the burning gas taking effect on the coil E' and the cone D will generate the gas from the crude petroleum, passing through the coil as supplied from the reservoir, or other source, through the supply section E. This construction and arrangement of the parts constitutes as I have demonstrated by actual usage, a very efficient generator and burner. The cone D is made of metal, preferably of cast metal, and acts not only as a support for the coil section E', but as a heat receiving and storage body, which co-operates with the direct action of the flame, on the coil E'. The cone D also acts as a deflector, to spread the flame from the burner, so that it comes in contact with the lower or outer surface of the conical helix E', and prevents the passing of the flame through the helix, which would otherwise occur to a considerable extent, if the cone D was not employed. It would be possible, however, to use the conical helix E', without the cone D, but that arrangement would not be so efficient. The cone D, as before stated, renders the generating action of the flame more efficient on the coil, in the way specified, and it also serves as a radiator, which co-operates with the flame passing beyond the rim of the cone in the heating action on the boiler or other body to be heated by the apparatus.

It should be noted, that the fire-pot bottom B is made in sectors, as a matter of convenience. Instead of winding the pipe E' into the form of a conical helix about the under surface of the cone D, a similar set of passages might be formed in the body of the cone itself, and the same be made a constituent part of the oil and gas supply conduit; or the cone D might be made hollow and used in the same way. The construction, I have shown, however, is in every way most desirable. I preferably embody the coil in the cone, so that the pipe of the coil will be about three-fourths embedded and have one-fourth of its surface exposed to the direct action of the flame. If it should be desired to use the device for other

oils than crude petroleum, the coil section E' must be of less extent.

What I claim, and desire to secure by Letters Patent of the United States, is as follows: 50

1. A combined oil-gas generator and burner, comprising a conical support acting as a deflector, positioned apex downward, a burner below the apex of said support, and a supply pipe or conduit leading to said burner, having a generating section wound into a conical helix about the under side of said support. 55

2. A combined oil-gas generator and burner, comprising a conical support positioned apex downward, a burner below the apex of said support, and a supply pipe or conduit leading to said burner, having a generating section wound about the said support and embedded therein on its under surface, in the form of a conical helix, substantially as described. 60

3. The combination with the conical support, arranged apex downward, provided with a central passage and a removable stopper therein, of the burner below the apex of said support, and the supply pipe or conduit, having a generating section wound about the under surface of said support in the form of a conical helix, substantially as and for the purpose set forth. 65

4. The combination, with a fire-pot, as A B, of the central conical support D, the central casting, C, with air-passages C', the hollow supporting legs d, secured to the conical support D, and, the central casting C, the supply pipe E E' E², having its generating section E', wound about and partially embedded in the under surface of the support D, the burner F, the removable plug D', and the drip C², all the said parts being arranged and operating, substantially as described. 70

In testimony whereof I affix my signature in presence of two witnesses.

MICHAEL BECK.
